Primary Examiner — Khawaja Anwar*Assistant Examiner* — Taylor O Mortorff(74) *Attorney, Agent, or Firm* — Derek Fahey, Esq.; The Plus IP Firm, PLLC(57) **CLAIM**

I claim the ornamental design for an upper end of a cleaning apparatus, as shown and described.

DESCRIPTION

FIG. 1 is a front perspective view of an upper end of a cleaning apparatus;

FIG. 2 is a front view of the upper end of a cleaning apparatus;

FIG. 3 is a back view of the upper end of a cleaning apparatus;

FIG. 4 is a first side view of the upper end of a cleaning apparatus;

FIG. 5 is a second side view of the upper end of a cleaning apparatus;

FIG. 6 is a top view of the upper end of a cleaning apparatus; and,

FIG. 7 is a bottom view of the upper end of a cleaning apparatus.

The dashed or broken lines in the figures illustrate (1) lower portions of the cleaning apparatus and (2) a plurality of buttons on the upper end of a cleaning apparatus and form no part of the claimed design.

1 Claim, 7 Drawing Sheets(56)
